No. 37,359.

Patented February 28, 1905.

UNITED STATES PATENT OFFICE.

SAMUEL BORCHARDT, OF NEW YORK, N. Y.

DESIGN FOR A SANDAL.

SPECIFICATION forming part of Design No. 37,359, dated February 28, 1905.

Application filed December 31, 1904. Serial No. 239,237. Term of patent 14 years.

To all whom it may concern:

Be it known that I, SAMUEL BORCHARDT, of New York city, county of New York, State of New York, have invented a new, original, and ornamental Design for Sandals, represented in the accompanying drawing.

The figure of the drawing shows the design of the sandal in perspective.

What I claim is—

The ornamental design for a sandal as shown.

SAMUEL BORCHARDT.
